LUMINAIRE

George P. Wakefield, Vermilion, Ohio, assignor to International Telephone and Telegraph Corporation, New York, N.Y., a corporation of Maryland

Filed May 31, 1966, Ser. No. 2,462

Term of patent 14 years

(Cl. D48—23)

FIG. 1 is a perspective view of a luminaire embodying my new design;

FIG. 2 is top plan view thereof;

FIG. 3 is an elevation view of one of the duplicate ends of my luminaire design as seen from the plane of the line 3—3 of FIG. 1;

FIG. 4 is a fragmentary transverse cross-section view taken substantially along the plane of the line 4—4 of FIG. 1;

FIG. 5 is an enlarged fragmentary longitudinal cross-section view taken substantially along the plane of the line 5—5, FIG. 4;

FIG. 6 is an enlarged fragmentary cross-section view similar to FIG. 5, but taken along the plane of the line 6—6 of FIG. 4; and

FIG. 7 is an enlarged fragmentary bottom plan view

adjacent one side edge of my luminaire design as seen from the plane of the line 7—7, FIG. 3.

The dominant features of my design reside in the portions shown in full lines.

I claim:

The ornamental design for a luminaire, substantially as shown and described.
